Geo. P. Kinnel.
ATTORNEY.

UNITED STATES PATENT OFFICE.

ABRAHAM P. PELSER, OF GREENFIELD, MASSACHUSETTS.

COMBUSTION-CHAMBER CARBURETOR.

Application filed March 24, 1922. Serial No. 546,233.

To all whom it may concern:

Be it known that I, ABRAHAM P. PELSER, a citizen of the United States, residing at Greenfield, in the county of Franklin and 5 State of Massachusetts, have invented certain new and useful Improvements in Combustion-Chamber Carburetors, of which the following is a specification.

This invention relates to attachments to 10 furnaces, stoves, ranges, and the like, for supplying superheated air above the fire, and has for one of its objects to simplify and improve the construction and increase the efficiency and utility of devices of this character.

Another object of the invention is to 15 provide a device of this character which may be quickly applied, preferably to the fuel door, and without change in the door or the 20 fire chamber except to cut a relatively small aperture through the door and without interference with ordinary draft appliances, or the opening or closing of the door.

With these and other objects in view the 25 invention consists in certain novel features of construction as hereinafter shown and described and then specifically pointed out in the claims, and in the drawings illustrative of the preferred embodiment of the invention:—

Figure 1 is an elevation of a portion of the 30 wall of a furnace together with the fuel door with the improvement applied.

Fig. 2 is a section on the line 2—2 of Fig. 1.

Fig. 3 is a plan view, partly in section, of the improved device.

Fig. 4 is a side elevation of the parts illustrated in Fig. 3.

Fig. 5 is an end view of the parts shown in Fig. 3.

The improved device includes an internally threaded sleeve 10, adapted to bear at one end against a support, for instance the door 11 of a furnace. The door 11 is of the usual form and when provided with the usual guard member 12, the sleeve 10 will bear against the guard member as indicated in Fig. 2.

50 A short section of pipe 13 is threaded into the sleeve 10 at one end and extends through an aperture in the door 11 and likewise through the guard 12 when one is encountered, and provided at its outer end with a controlling valve 14, the latter likewise operating as a clamping means to couple the

sleeve 10 and pipe section 13 firmly in position upon the support.

Threaded into the inner or opposite end of the sleeve 10 is a longer section of pipe 60 15 having a plurality of coils 16 bent therein, as shown.

At its outer end the pipe 15 is threaded into a head member 17, the latter branching and provided with a spraying nozzle 18 65 at the terminal of each branch.

The nozzle devices are threaded into the branches, so that they can be readily renewed when burned out, and each provided with transverse clefts 19 through which the 70 heated air escapes.

The pipe 15 with its coil 16 is so located relative to the fire on the grate, that the air escaping through the clefts 19 will come in contact with the flame as it rises from the fuel and thus supply fresh highly heated air to the fuel and materially accelerate the combustion and thus effect a very material saving in fuel.

75 The following extract from a report from the Department of the Interior is applicable in the present case: "One-half of combustion takes place in the fuel bed and one-half in the combustion space above the fuel bed. The oxygen flowing up through the grate is all used as it passes through the first three or four inches of the fuel bed. Therefore, the addition of air above the fuel bed for completely 80 burning the gases and preventing smoke is 85 essential."

85 The improved device effectually accomplishes the above results with a simple and inexpensive device which may be quickly and readily applied and adapted to fire 90 chambers of various forms and sizes. The device may be of any required size or capacity to adapt it to fire chambers of varying sizes. The controlling valve will preferably be of brass, or other non-corrosive 95 metal or metallic compound.

100 The coils 16 are arranged flatwise relative to the fire, so that the air in passing through continually rises toward the nozzle, and the formation of pockets or retarding bends is 105 avoided, so that the flowing air is continuous from the intake valve 14 to the nozzle.

A stop pin 20 is preferably forced into the plugs 18 at the intersection of the clefts 19, as shown in Fig. 5, to increase the efficiency of the spraying action.

110 The preferred embodiment of the inven-

tion is disclosed in the drawings and set forth in the specification, but it will be understood that modifications within the scope of the claimed invention may be made in the construction without departing from the principle of the invention or sacrificing any of its advantages.

Having thus described the invention, what is claimed as new is:—

- 10 1. A device of the class described comprising a section of piping adapted to operate through the fuel door of a combustion chamber, a laterally branching tubular member connected to the inner end of the piping, 15 a nozzle device terminating each branch and each comprising a tubular plug closed at the outer end except for a plurality of transversely directed intersecting clefts, and a

baffle member at the intersection of the clefts, whereby the air passing through the plug 20 will be directed laterally through the clefts.

2. A device of the class described comprising a section of piping adapted to operate through the fuel door of a combustion chamber, a hollow head member connected 25 to the inner end of said piping, a tubular plug connected into said head and closed at the outer end except for a plurality of transversely directed intersecting clefts, and a baffle member at the intersection of the 30 clefts, whereby the air flowing through said pipes and plugs will be directed laterally through the clefts.

In testimony whereof, I affix my signature hereto.

ABRAHAM P. PELSER.
